UNITED STATES PATENT OFFICE.

ROY I. SIBLEY, OF GARDENA, CALIFORNIA.

FRUIT-GRADER.

1,353,075.

Specification of Letters Patent. Patented Sept. 14, 1920.

Application filed November 7, 1919. Serial No. 336,476.

To all whom it may concern:

Be it known that I, ROY I. SIBLEY, a citizen of the United States, residing at Gardena, in the county of Los Angeles and State of California, have invented new and useful Improvements in Fruit-Graders, of which the following is a specification.

This invention relates to an apparatus for grading or sorting spheroidal bodies according to sizes, and the invention has for its object to provide an apparatus of this character which is economical in power consumption, is of comparatively simple construction, and will efficiently sort or grade various sizes of spheroidal bodies such as nuts and fruits, for instance oranges, lemons and olives with rapidity, and which will discharge continuously the different grades of the articles being sorted and will operate continuously in the assortment.

The invention consists of the construction and details, forms of which are illustrated in the accompanying drawings and described and claimed hereinafter.

Figure 1 is a longitudinal vertical section through an embodiment of the invention, parts of the mechanism being indicated in section.

Fig. 2 is a transverse vertical section on line 2—2 of Fig. 1.

Fig. 3 is a plan view of a portion of one end of the apparatus, certain of the parts being broken away to illustrate construction details.

Fig. 4 is a side elevation of a portion of the apparatus showing the driving mechanism for certain of the elements.

Fig. 5 is a side elevation of the mechanism for relatively adjusting the spacing of the agitating rollers.

Fig. 5^a is a detail showing the clamping device to hold the adjusting means shown in Fig. 5.

Fig. 6 is a plan view of a portion of the frame of the apparatus showing tension means for the carrier tracks.

Fig. 7 is a side elevation of the apparatus shown in Fig. 6.

Fig. 8 is an enlarged detail of one of the adjusting blocks or bearings shown in Fig. 5.

Fig. 9 is a side elevation of a tensioning device for one of the transfer belt shafts.

Fig. 10 is a section on the line 10—10 of Fig. 9.

The apparatus thus shown includes a suitable framework 2 with an appropriate box or housing structure 3 upon which the various sorting mechanism, described hereinafter, is mounted.

The sorting or grading mechanism embodies an organization whereby spheroidal bodies can be rapidly and efficiently segregated, and it is obvious that as many different gradings or assortments can be had in one apparatus as may be desired by the duplication or combination in the one machine of an assorting mechanism, the description of one of which will suffice in so far as the details are concerned for another or others that may be incorporated in the one apparatus. In this case I have shown two sets of the sorting mechanisms.

Preferably, the top of the box structure 3 is provided with a hopper or receiving chamber 4, the sides of which are inclined to secure the proper distribution of the articles to be sorted or graded and which may be introduced into the upper chamber 4 by means of a feed belt or other suitable conveyor 5 having a driving device in the form of a roller 6 at one end which may be actuated through any suitable driving mechanism as the belt and pulley 7—8.

The articles to be sorted, such for instance as nuts of different kinds, olives or other fruit being continuously fed in by the feeder 5 distribute themselves over a bottom structure in the chamber 4 which comprises a series of floor forming slats 9 arranged with their edges parallel and spaced, in this case, longitudinally of the machine thus forming grooves or channels indicated at 10 through which the articles being graded may pass downwardly and rest upon or engage suitable means operative to keep the articles

being sorted in a substantially agitated condition to prevent them from binding in the sorting device.

The agitating means, preferably, comprises pairs of cylindrical devices or rollers 11 hereinafter termed the agitating rollers, and these are spaced between their adjacent faces to form a continuation of the channels 10 and between the adjacent faces of the 10 rollers the articles being graded are permitted to fall downwardly and will be engaged by and supported on carrier tracks to be hereinafter described; unless the articles are of such size that they will pass through 15 the spaces on either side of the carrier tracks and below the adjacent sides of a given pair of rollers 11.

The rollers are clearly shown in Fig. 1 as having their end portions of reduced diameter or forming stems 11^a which are supported in bearings 12 that are slidably adjustable transversely of the machine on ways or supports 13. This reduction of the ends of the agitating rollers 11 is for 20 the purpose of providing or producing widened spaces at the ends of these rollers so as to permit such of the articles being graded, as would not pass between the lower surfaces of the rollers of one pair and the 25 subjacent track, to be discharged at one end of the hopper or chamber 4 on to a subjacent transverse discharging belt indicated at 15.

The carrier tracks above referred to preferably comprise endless cord-like members indicated at T thus forming belts one of which is disposed in the vertical plane medially between a respective pair of the agitating rollers 11, and these tracks T being 30 movable act as carriers to advance the oversize articles or pieces that are supported thereon toward one or the other ends of the rollers 11 so as to bring them into the area at the discharge part or stem member 11^a of the rollers and at which they will be discharged and permitted to fall on to the adjacent discharge belt 15. The carrier tracks (or belts) T are mounted upon 35 respective pairs of pulleys or supporting wheels 16 those at one end of the tracks T being mounted fast on a driving shaft 17.

The desired tension of the endless tracks T may be maintained by means of a suitable tensioning device, a form of which is illustrated in detail in Figs. 6 and 7, as comprising a bearing block 18 in which the shaft 18^a of the respective pulley or idler wheel 16 is mounted. This bearing block 18 is adjustable along suitable ways 19 and 40 is connected at one side by a tension device in the form of a chain 20 adapted to be hooked temporarily to a suitable pin or other fixed part 21 on an adjacent portion of the frame of the machine. From this it will be 45 seen that the endless track forming members

T can be continuously driven so that their upper stretch will act as a support for the articles being sorted and will carry the oversize articles as above mentioned to the discharge end of the rollers 11 operating with 50 respect to a given track T.

For the purpose of preventing the jamming or sticking of the articles being sorted in between the associate track T and the relative rollers 11, the rollers are preferably 55 rotated on their own axes in such direction that their adjacent faces sweep upwardly with a tendency to brush the nuts or fruits that are being handled inwardly toward the medial plane and thus prevents them from 60 being caught in the spaces therebetween and above the supporting track T.

This desired rotation in the necessary direction of the rollers 11 is secured by any suitable mechanism, in the present case, indicated as comprising spiral gears 22 mounted on the ends of the reduced parts 11^a of the rollers, these gears intermeshing with complementary gears 23 which are mounted on the shaft 24 extending transversely across the machine and supported in appropriate bearings as 25. Rotation of the shaft 24 is secured through means of appropriate connections to the shaft 17. In this case, the latter shaft is provided with 95 a sprocket wheel 26 having a chain 27 running over a sprocket pinion 28 fastened adjacent to one end of the shaft 24.

Power to drive the main shaft 17 may be derived from any suitable source as through 100 a large gear 30 secured on one end thereof with a pinion 31 fast on a short shaft 32 mounted in appropriate bearings and having on its outer end or suitable portion a driving pulley P over which a belt may be 105 extended to any other countershaft as may be convenient.

For the purpose of securing variation of the spacing of the rollers 11 in respective pairs and thus to adapt the machine to the 110 assortment or segregation of nuts or fruits of different sizes as above suggested, the bearings 12 of the roller stems are slidable along suitable supports or ways 13, and an adjusting mechanism attached to these bearings 12 is plainly illustrated in Figs. 5, 5^a and 8 in which the blocks are shown as adjustably connected to one or another of suitable transversely extending links 35, one roller 11 of one pair being attached, as for 115 instance, by a clamp screw 36 to its respective adjusting rod 35, the latter being slotted at 35^a to take the clamp screw 36.

One of the agitating rollers 11 is connected to one rod 35 and the other roller of 125 the pair is connected to the other rod 35 and these rods are shown as extended endwise and connected at diametrically opposite points to a crank device in the form of a disk 37 having a shaft 38, one link being 130

connected at 39 to one side of the disk and the other link connected at 40 to the opposite side, so that upon the rotation of the crank device or disk 37 the links 35 will be shifted simultaneously in opposite directions and therefore will move the rollers 11 of one pair either toward each other or from each other according to the direction of rotation of the crank device 37 which 5 may be operated by means of a lever 41 extending upwardly from one side of the disk and provided with any suitable setting device as a clamp screw 42 designed to bind the latter at the desired position upon a 10 fixed part as a bracket 43.

The shaft 38 upon which the adjusting device 37 is mounted may be extended along the outer side of the casing or frame as indicated in Figs. 2 and 3, so that both ends 20 of each of the rollers 11 are moved equal distances and thus secure uniform setting of the rollers of each pair, and since all of the bearings of the several rollers 11 of one assorting mechanism are connected to and 25 simultaneously operated by the one adjusting device 37, it will be seen that a uniform change for different assortments will be obtained at one setting of the adjusting device 37.

30 From the above it will be seen that when a charge containing various sizes of articles to be sorted is introduced into the chamber or hopper 4 the articles will spread out and pass downwardly into the channels 10 between the pairs of rollers 11 and the undersize pieces or articles will pass between the lower faces of the rollers and the adjacent or upper surface of each of the carrier tracks or belts T.

40 The undersize articles, in the present case, fall upon endless traveling transfer belts forming substantially a continuous floor beneath the grading rollers 11 and these belts, designated respectively at 45, are mounted 45 at their ends upon rollers or pulleys 46, the rollers at one end being fastened on a drive shaft 47 which extends transversely across the machine and is provided with a sprocket 48, Fig. 4, driven by a sprocket chain 49 passing over suitable idlers or guide sprockets 50 appropriately positioned and said chain also runs around a master sprocket 51 which is secured on an intermediate shaft 52 to secure a change of direction of 55 rotation, the shaft being provided with a gear 53 meshing with a gear 54 of similar size and which is secured on the main shaft 17.

60 The tension of the several transfer belts 45, which are shown as spaced edgewise from each other by suitable guides 45^a, Fig. 2, is controlled and may be varied by suitable adjustment of end rollers 46 mounted on a shaft 55, Figs. 1, 9 and 10, which shaft 65 is supported in bearing blocks 56 these being

slidably engaged with ways or guides 57 attached to suitable portions of the framework 2. Desired tension of the belts 45 is obtained by shifting the blocks 56 on their ways through the adjustment of a set screw 70 58, one provided for each block 56, and which is turnable in a threaded projection or nut portion 59 fixedly mounted on the frame.

In the event that only a single assortment 75 of the article is being made, the oversize nuts or fruit are carried outwardly by the discharge belt 15 to a suitable receiver while the undersize nuts or fruit falling to the transfer belts 45 are carried similar to a 80 suitable point of the discharge separate from the discharge belt 15. However, if it is desired to make any further segregation or grading of the nuts passing between the several rollers 11 and the carrier tracks 85 85 and received upon the belt 45 then another organization of the grading mechanism is arranged below the upper organization and the carrier belts 45 will discharge their burden on to one end of the subjacent sets of 90 rollers 11 and the operation, as above described, will be repeated, the undersize articles passing through the roller organization being discharged into a receiving box indicated at 60 and shown as provided with 95 inclined bottoms so that all of the articles whether fruit or nuts will be directed toward a central trough 61 which may be provided with a discharge belt 62. The oversize articles from the lower sorting mechanism 100 will be shifted toward discharge belts 15^a, Fig. 1, and by this carried away to a separate receiver.

The discharge belts 15 and 15^a are supported upon suitable rollers certain of which 105 have shafts 63, Fig. 4, provided with gears or bevel pinions 64 that are engaged by complementary pinions 65 fast on shafts 67 carrying sprocket wheels or other power receiving means 68 that are engaged by an 110 endless sprocket chain 69 which extends over to and is driven by a master sprocket 70 secured on the shaft 17.

The endless carrier tracks T of the lower sorting mechanism are operated through 115 their respective pulley wheels, one of which for each belt is secured on a shaft 71 disposed below the upper shaft 17 and having suitable driving connections as sprocket gear 72 so that the shafts are driven together. Power can be taken from the lower shaft 71 to drive the lower set of rollers 11 120 by means of sprocket gear indicated at 73.

By relatively staggering the pairs of coordinate rollers 11 with respect to the upper 125 series and the lower series, the lower stretch of the carrier tracks T can be covered and protected by the lower longitudinally extending slats shown at 9^a, Fig. 2, which may be of hollow form or of arcuate cross 130

section to provide space for the lower stretch of the adjacent track T to run in.

Various changes may be made without departing from the spirit of my invention as claimed.

I claim:

1. An apparatus for grading spheroidal bodies including a plurality of pairs of rollers spaced at different distances apart, 10 one end of said rollers being reduced in diameter, a conveyer track extending longitudinally between and below each pair of said rollers, a conveyer extending transversely under the reduced ends of said

15 rollers, and a conveyer extending longitudinally below each track conveyer and the pair of rollers above it.

2. An apparatus for grading spheroidal bodies including a plurality of pairs of rollers spaced at different distances apart, 20 one end of said rollers being reduced in diameter, a conveyer track extending longitudinally between and below each pair of said rollers, a conveyer extending transversely under the reduced ends of said rollers, and a conveyer extending longitudinally below each track conveyer and the pair of rollers above it; and a guide 25 standing between each of said latter conveyers.

3. An apparatus for grading spheroidal bodies including a plurality of pairs of rollers spaced at different distances apart, one end of said rollers being reduced in diameter, a conveyer track extending longitudinally between and below each pair of said rollers, a conveyer extending transversely under the reduced ends of said rollers, and a conveyer extending longitudinally 30 below each track conveyer and the pair of rollers above it; a receiving box below said latter conveyers and a discharge belt in the bottom of said receiving box.

4. A grading device consisting of a series 45 of trough-like sets of side members and a bottom member all disposed to form lateral spaces for the outlet of undersize bodies, said members coöperative to advance the oversize bodies toward one end of the members, and means for simultaneously laterally and oppositely adjusting relative side members of each set.

5. An apparatus for grading spheroidal bodies, comprising a pair of rotary, parallel 55 rollers, with means for turning the paired rollers so that their adjacent faces move upward; the rollers having certain ends reduced in diameter to increase the transverse space between the same; and means disposed 60 medially below the rollers for forming outlet spaces for undersize bodies and operative to advance the oversize bodies supported thereon toward the increased space at the ends of the rollers.

6. An apparatus for grading spheroidal

bodies; comprising a pair of rotary, parallel rollers, with means for turning the paired rollers so that their adjacent faces move upward; the rollers having certain ends reduced in diameter to increase the transverse space between the same; and means disposed medially below the rollers for forming outlet spaces for undersize bodies and operative to advance the oversize bodies supported thereon toward the increased space at the ends of the rollers, said last named means including endless traveling belts.

7. An apparatus for grading spheroidal bodies, comprising a series of pairs of rotary, parallel rollers, with means for turning the paired rollers so that their adjacent faces move upward; the rollers having certain ends reduced in diameter to increase the transverse space between the same; and means disposed medially below the rollers for forming outlet spaces for undersize bodies and operative to advance the oversize bodies supported thereon toward the increased space at the ends of the rollers.

8. An apparatus for grading spheroidal bodies, comprising a series of pairs of rotary, parallel rollers, with means for turning the paired rollers so that their adjacent faces move upward; the rollers having certain ends reduced in diameter to increase the transverse space between the same; means disposed medially below the rollers for forming outlet spaces for undersize bodies and operative to advance the oversize bodies supported thereon toward the increased space at the ends of the rollers; and discharge means extending transversely to the discharge ends of the pairs of rollers in the series to carry away the segregated oversize bodies.

9. An apparatus for grading spheroidal bodies, comprising a series of pairs of rotary, parallel rollers, with means for turning the paired rollers so that their adjacent faces move upward; the rollers having certain ends reduced in diameter to increase the transverse space between the same; means disposed medially below the rollers for forming outlet spaces for undersize bodies and operative to advance the oversize bodies supported thereon toward the increased space at the ends of the rollers; and slats for covering the spaces between adjacent rollers of two pairs.

10. An apparatus for assorting spheroidal bodies according to size, comprising a plurality of series of spaced rollers, which latter are arranged in pairs with upwardly turning, adjacent faces; means disposed medially below the spaced and paired rollers to form supports for oversize bodies and permit undersize bodies to escape laterally; means for rotating all of the rollers in paired relations; and means for driving the

supporting means so as to carry oversize bodies to respective and separate discharges for each series.

11. An apparatus for assorting spheroidal bodies according to size, comprising a plurality of series of spaced rollers, which latter are arranged in pairs with upwardly turning, adjacent faces; means disposed medially below the spaced and paired rollers to form supports for oversize bodies and permit undersize bodies to escape laterally; means for rotating all of the rollers in paired relation; means for driving the supporting means so as to carry oversize bodies to respective and separate discharges for each series; and transfer means for transferring the undersize bodies of one series to the head of another series.

12. An apparatus for assorting spheroidal bodies according to size, comprising a plurality of series of spaced rollers, which latter are arranged in pairs with upwardly turning, adjacent faces; means disposed medially below the spaced and paired rollers to form supports for oversize bodies and permit undersize bodies to escape laterally; means for rotating all of the rollers in paired relation; means for driving the supporting means so as to carry oversize bodies to respective and separate discharges for each series; and separate oversize body discharge means for each series.

13. An apparatus for grading spheroidal bodies including a plurality of pairs of rollers spaced at different distances apart, one end of said rollers being reduced in diameter, a conveyer track extending longitudinally between and below each pair of said rollers, and a conveyer extending transversely under the reduced ends of said rollers, and a conveyer extending longitudinally below each track conveyer and the pair of rollers above it; a plurality of pairs of rollers spaced at different distances apart located below said conveyers, said latter rollers being reduced at one end, a conveyer extending transversely under the reduced ends of said latter rollers, and a track conveyer extending between and below said latter rollers.

14. An apparatus for grading spheroidal bodies including a plurality of pairs of rollers spaced at different distances apart, one end of said rollers being reduced in diameter, a conveyer track extending longitudinally between and below each pair of said rollers, a conveyer extending transversely under the reduced ends of said rollers, and a conveyer extending longitudinally below each track conveyer and the pair of rollers above it; a plurality of pairs of rollers spaced at different distances apart located below said conveyers, said latter rollers be-

ing reduced at one end, a conveyer extending transversely under the reduced ends of said latter rollers, and a track conveyer extending between and below said latter rollers; a receiving box below said latter rollers, and a discharge belt in the bottom of said box.

15. An apparatus for grading spheroidal bodies including a plurality of pairs of rollers spaced at different distances apart, one end of said rollers being reduced in diameter, a conveyer track extending longitudinally between and below each pair of said rollers, a conveyer extending transversely under the reduced ends of said rollers, and a conveyer extending longitudinally below each track conveyer and the pair of rollers above it; a plurality of pairs of rollers spaced at different distances apart located below said conveyers and staggered with relation to said first rollers, said second rollers being reduced at one end, a conveyer extending transversely under the reduced ends of said second rollers, and a track conveyer extending between and below said latter rollers.

16. An apparatus for grading spheroidal bodies including a plurality of pairs of rollers spaced at different distances apart, one end of said rollers being reduced in diameter, a conveyer track extending longitudinally between and below each pair of said rollers, a conveyer extending transversely under the reduced ends of said rollers, and a conveyer extending longitudinally below each track conveyer and the pair of rollers above it; and means for simultaneously adjusting said pairs of rollers closer together or farther apart.

17. An apparatus for grading spheroidal bodies including a plurality of pairs of rollers spaced at different distances apart, one end of said rollers being reduced in diameter, a conveyer track extending longitudinally between and below each pair of said rollers, and a conveyer extending transversely under the reduced ends of said rollers, and a conveyer extending longitudinally below each track conveyer and the pair of rollers above it; a plurality of pairs of rollers spaced at different distances apart located below said conveyers, said latter rollers being reduced at one end, a conveyer extending transversely under the reduced ends of said latter rollers, and a track conveyer extending between and below said latter rollers; means for simultaneously adjusting said first pairs of rollers closer together or farther apart, and means for simultaneously adjusting said second pairs of rollers closer together or farther apart.

In testimony whereof I have signed my name to this specification.

ROY I. SIBLEY,
